(57) **CLAIM**

The ornamental design for a cooler, as shown and described.

DESCRIPTION

FIG. 1 is a front upper isometric perspective view of a cooler;
FIG. 2 is a rear lower isometric perspective view thereof;

FIG. 3 is front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front upper isometric perspective view of a cooler
with the lid removed;

FIG. 10 is a rear upper isometric perspective view thereof;
FIG. 11 is a front upper isometric perspective view of a
cooler lid;

FIG. 12 is a rear lower isometric perspective view thereof;
FIG. 13 is a front upper isometric perspective view of a
cooler with the lid removed and handles pulled out;

FIG. 14 is a left side elevation view thereof;

FIG. 15 is a front upper isometric perspective view of a
cooler with the handles pulled out; and,

FIG. 16 is a right side elevation view thereof.

The bottom portion and the lid are shown separately for
clarity of illustration.
